UNITED STATES PATENT OFFICE.

CLEETIS BROWN, OF MANTECA, CALIFORNIA.

CARD GAME.

Application filed March 7, 1928. Serial No. 259,704.

This invention relates to indoor card games and particularly to one played with a deck of cards, my principal object being to arrange the cards so that in the playing of the 5 game, which is particularly intended for chemistry students, the players will learn various fundamental facts of inorganic chemistry besides being entertained by the game.

The game is based upon the facts that metallic elements of those of displacement series 10 (+'s) combine with non-metallic elements and radicals (-'s) forming compounds; and upon the solubility of such compounds in water.

15 The main facts concerning chemistry which are learned are as follows:

1. Valence.
2. Ionization.
3. Common elements.
4. Common radicals.
5. Activity or displacement series.
6. Names of compounds.
7. Formulas.
8. Compounds not soluble in water.
9. Metals.

25 10. Non-metals.
11. One type of chemical reactions that go to an end.
12. Elements that are gases under ordinary 30 conditions.

The above objects are carried out by marking or printing the cards in a particular manner as shown on the drawings and as will now be explained.

35 On the drawings Figs. 1-3 show separate pairs of cards arranged together to form separate compounds or formulas. Fig. 4 is a face view of a single other card.

The cards, of which there are a suitable 40 number in the deck (about 48), are divided into groups embracing common radicals and elements, both metallic and non-metallic. On each radical card 1 the name of the radical is prominently printed as at 2; on each 45 metallic element card 3 the name of the element 4 is likewise prominently printed; and on each non-metallic element card 5, the name of the element 6 is printed. Also printed on all the cards under the identifying names is data 7 as to the solubility or insolubility of 50 the substance in question and a list of other substances with which such substance forms a compound of soluble or insoluble nature.

55 The metallic element cards are provided with prominently displayed numbers 8, these numbers being arranged from 1 up and cor-

responding to the relative activity of the element. In other words the potassium card is numbered 1, this being the element having the greatest activity in the displacement 60 series of metals replacing any other metallic element, provided, of course, that the compounds of the other elements are soluble in water.

In all four corners of all the cards are placed + or - signs 10, corresponding to the metallic or non-metallic properties of the substances which the cards represent, and the numbers of such symbols designate the 65 valence of the element or radical of the card. 70 These signs also show the electric charges or ions carried when the element is in a compound and in a water solution. Under the signs is the chemical symbol 11 of the substance which, in the different corners of the 75 cards are printed in different atomic values as is necessary when combining the substance with others of different kinds. Under these symbols is printed the prefix or suffix 12 of the compound arranged so that when a pair 80 of cards are properly matched, the name of the compound formed will appear in easily read order on the cards as clearly evident from Figs. 1 to 3. Likewise the symbols 11 are similarly arranged so that the formula of 85 the compound thus formed will also be easily read.

The game is best played by a pair of partners against one or more pairs of opponents, and the object is particularly to associate the 90 cards in proper compound forming relation, and also if possible to use the cards having higher values (as determined by the numbers 8 on the cards) than those laid down by the opponents, so as to take the tricks. Various arbitrary rules may be prepared as to 95 the mode of playing and as to the number of points counted for the tricks, for penalties and other features, which rules of course can be changed to suit if desired.

In playing the cards are all dealt out to the 100 players. The first player then lays down any card and is followed by his partner, whose card must be of opposite ionization from the first and which to count anything must form 105 a correct formula or compound with the first card, and must be laid down in a certain definite relation. In other words it is not sufficient that the two cards merely be laid down adjacent each other on the table, but 110 the suffix card of a compound must be placed beyond the prefix card, and they must be

- turned so that the atomic values represented in the corners of the cards will properly co-operate with each other to give the correct formula intended to be represented by the cards. In other words the cards must be disposed so that the name of the compound and the formula thereof can be read directly across between adjacent corners of the two cards as clearly shown in the drawings.
- 10 In forming the compound "tin phosphate" for instance, it is necessary to place the cards so that the correct formula $\text{Sn}_3(\text{PO}_4)_2$ will appear in that order on the adjacent corners of the cards. If the cards are wrongly laid down, so that the formula reads $\text{Sn}(\text{PO}_4)_3$, for instance the opponent has an opportunity to correct the error and correct it by properly turning the card and the original player loses a certain number of points. If the opponent 20 in turn does not properly correct the error, one of the original players has another opportunity to again call such error and correct it, and so on till the correct formula appears.
- 25 In thus playing the game it will be evident that the players soon learn the proper formulas, their names, whether soluble or insoluble, as well as other facts which may be gleaned from an inspection of the matched 30 cards.

One of the opponents now plays. If the compound above formed is soluble he may replace the plus or positive card provided he has one of higher displacement value (as indicated by the numbers 8 on the cards) or he can add a minus or negative card to make the compound insoluble. If the compound is already insoluble or the opponent cannot properly alter the composition of the same, 40 he tries to make a compound of his own as above described, which compound in turn may be changed by the first player, and so on. Any such changes successively made by one side or the other adds a certain number of 45 points to their score. When all the players have made compounds, the one of the highest value on the board takes the trick, and the playing is then resumed with a clear board.

In the illustration on the drawings, in 50 which Figs. 1-3 represents three different compounds formed by three sets of partners, the second compound being of the highest value the players corresponding to such compound take the trick. If the formula represented by the cards in Fig. 3 should at that time represent the lowest value formula on the board, the higher value card of Fig. 4 55 may be substituted for the lower value card of the same ionizing properties, so as to form

strontium acetate instead of zinc acetate—a 60 correct chemical formula and compound. The valences of the elements, etc., printed in the corners of the cards, and the atomic values of such substances given below the valence signs, provide the necessary data for enabling 65 the formula to be readily made without any knowledge of chemistry being had. This is because the least common multiple of the valences and atomic values of the two elements being combined, give the correct 70 formula, and such multiple can be readily computed by the player. In Fig. 1 for instance, we have $\text{Sn}_3 \times 2 + \text{S} = 6$ and

$$(\text{PO}_4)_2 \times 3 - \text{S},$$

also equaling six.

From the foregoing description it will be readily seen that I have produced such a game as substantially fulfills the objects of the invention as set forth herein.

While this specification sets forth in detail the present and preferred construction of the device, still in practice such deviations from such detail may be resorted to as do not form a departure from the spirit of the invention, 85 as defined by the appended claims.

Having thus described my invention what I claim as new and useful and desire to secure by Letters Patent is:

1. A game comprising cards all having 90 the names of different chemical elements thereon, whereby a combination of certain pairs of the cards will represent a chemical formula, each card having the ionization and valence signs of the corresponding element 95 printed in all the corners of the card.

2. Game cards as in claim 1, in which the different atomic values of the element are closely associated with such signs, there being 100 one such value in each corner.

3. Game cards as in claim 1, each having the chemical symbol of the corresponding element, and the prefix or suffix of a compound of which said element may be a part, 105 printed adjacent the corners of the card.

4. A game comprising cards all having the names of different chemical elements thereon, different atomic values of each element being printed in the different corners of the corresponding card, whereby to enable any one of such cards being separately paired with a number of other cards representing different chemical elements to form a corresponding number of different chemical compounds.

In testimony whereof I affix my signature.

CLEETIS BROWN.
